A. E. STEVENS

SELECTOR RACK FOR AUTOMATIC TELEPHONE SYSTEMS

Filed Aug. 2, 1921

UNITED STATES PATENT OFFICE.

ALTON E. STEVENS, OF PROVIDENCE, RHODE ISLAND.

SELECTOR RACK FOR AUTOMATIC TELEPHONE SYSTEMS.

Application filed August 2, 1921. Serial No. 489,289.

To all whom it may concern:

Be it known that I, ALTON E. STEVENS, citizen of the United States, residing at Providence, in the county of Providence and State of Rhode Island, have invented certain new and useful Selector Racks for Automatic Telephone Systems, of which the following is a specification, reference being had therein to the accompanying drawings.

10 My invention relates particularly to racks used in the central switchboards of private telephone systems, for supporting the selector mechanism, and has for its object, the simplification of the construction of such racks, and the facilitation of their manufacture.

15 In the drawings illustrating the principle of my invention, and the best mode now known to me of embodying the same in operative structure:

Fig. 1 is a plan of a bracket integral with a backboard, not shown.

Fig. 2 a plan of the top of jack end of the selector rack;

25 Fig. 3 a plan of the rack with top piece removed;

Fig. 4 a front elevation of the rack, and bracket;

30 Fig. 5 a side elevation of the rack, bracket and back-board;

Fig. 6 a simplified diagram of the circuits of an automatic telephone system employing these racks.

Referring to Figs. 1, 2, 3 and 4, to a back-board 1, Fig. 5, are permanently secured a bracket 2, and two posts 3. The bracket 2, Fig. 1, is slotted at 4, and has secured to its upper surface by eyelets 6, a sheet of insulating material 7, carrying a number of jack springs, as 8 arranged radially to conform to the radius of the slot 4, and "staggered" as shown. The jack springs 8 are secured by eyelets 9, Figs. 1 and 4.

The selector rack is removably secured to the bracket 2, and back-board 1, and consists of two angle irons 10 held at the bottom by a strap 11, Figs. 4 and 5, which is riveted to the angles, and a top piece 12, Figs. 2 and 4, also riveted to the angles. On the face of the angles are pairs of pins 13 arranged one pair above another, each pair to receive a selector 14, Figs. 3, 4, and 5, the selectors thus being arranged in a vertical series, and each selector being secured by screws 15 in pins

13; the selector frames having holes to slide over the pins.

Adjacent to each pair of pins and secured to the angles, is a horizontal metal arch 16, Figs. 3, 4 and 5, carrying a segment of insulating material 17, each segment having a series of holes 18 for the reception of vertical metal contact bus-bars 19, Fig. 4, said holes 18 being arranged radially around a common centre at which is located the shaft 20, Fig. 3, of each selector mechanism, when this latter is in its place on the pins 13.

The top piece 12 has a curved slot 21, Fig. 2, so that the contact bus-bars 19, held in the segments 18 may pass through without contacting the metal.

Secured to the top piece 12 by rivets as 22, is a segment 23 of insulating material, having holes 24 corresponding in position with the holes 18, in segments 17.

A second segment of insulating material 25, Figs. 2 and 4, of the same shape as 23, is also secured to the top piece 12 by the same rivets 22, as is the first segment 23; the said rivets 22 having a shoulder whereby the two segments are held a distance apart corresponding to the diameter of the contact bus-bars 19. The second segment 25 has holes as 26, these holes being "staggered" and positioned the same as the jacks 8 in the piece 7, of the bracket 2.

The contact bus-bars 19, see Fig. 4, are given a "bayonet" bend near their upper end; that is, two right angle bends as illustrated. When these contacts bus-bars 19 are assembled in the rack, one for each hole as 18 in segments 17, the rods extend vertically from the top segment 23 through the entire series of segments as 17, to the bottom of the rack, the bent ends of the bus-bars 19 being "staggered", so that the short vertical ends extend through the holes as 26 in segment 25, these short ends forming plugs which engage and contact the jack springs 8, when the plugs are pushed up through the eyelets 9 which secure the springs 8 to the piece 7.

The parts of the selector rack are assembled as follows: The pins 13, see Figs. 4 and 5, are staked into the angles 10; the top piece 12 and the strap 11 are then riveted on, thus holding the rack together; next the arches 16, carrying the segments 17 are riveted to an angle at each end, and lugs

27, designed to support a line terminal board 28, are staked into the left hand angle. Next, the segment 23 is riveted to top piece 12, and a contact bus-bar 19 run down through 5 each of the holes in each of the segments 23, the bent ends being above this piece 23, and staggered so that the segment 25 may be pushed down over them and riveted into place on the upper end of rivets 22.

10 The horizontal bends in the contact bus-bars 19, between the two segments 23, 25, lock the said bus-bars 19 against longitudinal movement, which are thus held for their entire length in insulating material, and 15 have their upper ends so positioned, that each will enter an eyelet hole as 9 in piece 7, and contact a jack spring as 8; the said jack springs having a tag 102, to which wires may be soldered to connect them to 20 corresponding springs on other rack brackets. A line terminal board 28, Figs. 3, 4, and 5, of insulating material is secure to the lugs 27.

A battery jack has one member 29, Fig. 1, 25 secured to bracket 2 and carries two contact jacks 30, 31; while a second member 32, secured to top piece 12, carries two jack plugs 33 and 34, designed to engage the contact jacks 30, 31, when the rack is inserted in place in relation to the bracket 2. The jacks are shown in circuit, in Fig. 6.

Adjacent to each selector position, on the line terminal board 28, are three spring jacks as 37, 38 and 39, Figs. 5 and 6; and in each 35 selector frame as 14, are three jack plugs 40, 41 and 42, in an insulating block 43, Fig. 4, and designed to contact jacks 37, 38, and 39, when a selector is installed on the pins 13.

40 The line terminal board also carries three connectors for the lines assigned to each selector, as at 43, 44 and 45, Figs. 4 and 6.

To install the selector rack in the bracket 2, on the back-board 1, the pins 36, on the 45 sides of the rack are moved up into the slots 35, Fig. 5, in the bracket, thereby causing the plug ends of the contact bus-bars 19, to register correctly with the eyelets 9 in the jack springs 8, Figs. 1 and 4; the jack 50 plugs 33 and 34 in the top piece 12 engaging the contact jacks 30, 31 of the battery jack secured to the bracket 2. The rack is retained in position by two screws 50, through holes 51, screwed into posts 3.

55 Each selector, as 14, Figs. 3, 4 and 5, is secured on pins 13 by screws 15, and carries an arm 47, on which is mounted a spring contact shoe 48, the arm 47 being secured to shaft 20 and ratchet wheel 49 but insulated 60 from them. As the shaft 20 is caused to rotate, the arm 47 turns with it, and causes shoe 48 to successively contact the contact bus-bars 19. The teeth in the ratchet wheel 49 are spaced corresponding to the spacing 65 of the contact bus-bars 19, so that each step

of the ratchet wheel, advances the contact shoe to the next succeeding contact bus-bar.

A brush 51 maintains electric contact with the arm 47 during the latter's rotation, for circuit reasons, in a well known manner. 70

Complete selector mechanism has not been shown in Figs. 3, 4, 5 as this forms no part of the present invention, but for the purpose of explanation, it has been illustrated diagrammatically in Fig. 6. 75

As there may be several racks in each system, and as the contact bus-bars in the same positions in each rack are connected to the same telephone station line, each jack spring as 52, Fig. 1, on the first bracket, is connected to a corresponding jack spring as 53, 54, on other brackets in a system by a wire as 55, 56, these wires being laced together in the form of a multiple cable, as in common practice. 80

I will now describe the operation of a simple automatic telephone system in connection with my invention. Referring to Fig. 6, "A" represents the circuits and apparatus of a calling telephone station, and "B" the selector mechanism. "C" represents the circuits and apparatus of a called telephone station, and "D" the selector mechanism of same. 85

A wishes to call C. The receiver 57 is 90 lifted, causing hook 58 to break from 59, and bringing contacts 60, 61 together, thereby completing a holding circuit from positive side 64 of battery 65, through jack 30, wire 66, connector 45, contacts 60, 61, primary 69, transmitter 70, wires 71, 72, connector 43, jack 37, connecting magnet 73, jack 38, wire 64, jack 31 to negative side 69' of battery 65; connecting magnet 73 is thereby energized and attracts armature 74, 100 which causes spring detent 75 to engage ratchet wheel 49, and retain it in each successive step to which it may be moved. Armature 74 has comparatively weak adjustment, while armature 75 is adjusted 110 stiffly, and is not attracted on account of the resistance of primary 69 and transmitter 70, in the circuit. 115

Stepping key 62 is now pressed into contact with 63 four times, this being the call number of station "C". A stepping circuit is thereby completed four times, from positive side 64 of battery 65, through jack 30, wire 66, connector 45, contacts 60, 61, 63, key 62, connector 44, jack 39, stepping magnet 67, jack 38, wire 64, jack 31, to negative side 69 of battery 65. Stepping magnet 67 is energized four times, attracting armature 68, and causing pawl 76 to engage, ratchet 49, and step it around four teeth, thus bringing the shoe 48 into contact with contact bus-bar 77, upon which it will come to rest. 120

Ringing key 78 is now pressed into contact with 79 and completes a connecting and 125 130

- ringing circuit, by short circuiting the primary 69 and transmitter 70; the elimination of this resistance causing enough current to flow through magnet 73 to attract 5 connecting armature 75, which causes contact between springs 80, 81, and completes a ringing circuit as follows:—from positive side 64 of battery 65, through jack 30, wire 66, connector 45, contacts 60, 61, 79, key 10 78, wires 71, 72, connector 43, jack 37, springs 80, 81, brush 51, arm 47, shoe 48, contact bus-bar 77, wires 78, 82, connector 83, ringer 84, contacts 85, 86, connector 87, jack 88, magnet 89, jack 90, wires 91, 64, jack 31, 15 to negative side 69 of battery 65. The ringer 84 is therefore operated, and signals the party at station "C".
- The ringer 84 is of high resistance and the magnet 89 is of low resistance, and does 20 not attract its armature which is stiffly adjusted, strongly enough to operate same.
- The armature 75 is so adjusted, in a manner well known, that after it pulls up against the end of magnet 73, it sticks there after 25 the key 78 is released, and the resistance of 69 and 70 re-introduced.
- The called party at station "C" now removes receiver 92 from hook 86, causing 93 to contact 94, and the parties at the two stations 30 may now converse, the transmitter at each station being energized over their holding circuits as before described.
- The talking circuit is as follows:—from common wire 95, through connector 45, contacts 60, 61, primary 69, transmitter 70, wires 71, 72, connector 43, jack 37, springs 80, 81, brush 51, arm 47, shoe 48, bus-bar 77, wires 78, 82, connector 83, transmitter 96, primary 97, contacts 94, 93, connector 98, 40 back to common wire 95. Transmitters A and C are each energized over individual battery circuits, the energizing circuit of A being as follows:—from positive side 64 of battery 65, through 30, 66, 45, 60, 61, 69, 70, 45 71, 72, 43, 37, impedance 73, wire 64 to negative side 69' of battery 65. The energizing circuit of station C may be traced in a like manner.
- Fluctuations of current through the primaries 69, 97, caused by transmitters 70, 96, 50 are repeated by induction in secondaries 99, 100, and affect the receivers 57, 92, in a well known manner, and conversation can be carried on.
- When the receiver 57 is replaced on hook 58, the member 60 breaks contact with 61, thereby interrupting the holding circuit and causing the magnet 73 to become de-energized, the armature 74 returning to normal 55 position, and causing detent 75 to release ratchet wheel 49, permitting the latter, and the arm 47 and shoe 48, to return to normal position by reason of a suitable spring, shown at 101, Fig. 4.
- Having now described the features and

operation of my invention, and desiring to protect the same in the broadest manner legally possible,

What I claim is:—

1. A vertical rack; horizontal insulating spacers, one above another; fixed vertical contact bus-bars retained in their relative positions by said spacers; selectors for said rack; and means whereby said selectors may successively engage said bus-bars. 70
2. A vertical rack; horizontal insulating spacers, one above another; vertical contact bus-bars retained in their relative positions by said spacers; pins perpendicular to the face of the said rack; one or more selector frames with holes therein to allow a selector to be removably mounted upon said pins; the said contact bus-bars being each engageable by the wiper of said selector. 80
3. A vertical rack; horizontal insulating spacers, one above another; vertical contact bus-bars retained in their relative positions by said spacers; pins perpendicular to the face of the rack; one or more selector frames with holes therein to allow a selector to be removably mounted on said pins; the said contact bus-bars being each engageable by the wiper of said selector; jacks secured to said rack whereby the selector circuits become connected or disconnected 85 when the selector is mounted on, or de-mounted from the selector rack. 90
4. A vertical rack; horizontal insulating spacers, one above another; vertical contact bus-bars retained in their relative positions by said spacers; pins perpendicular to the face of said rack for the purpose of receiving and positioning selectors; a terminal board secured to the said rack and having terminals therein horizontally adjacent to each selector position. 100
5. A vertical rack; horizontal insulating spacers, one above another; vertical contact bus-bars retained in their relative positions by said spacers; pins perpendicular to the face of the rack; one or more selectors with frames having holes therein whereby they may be removably mounted on said pins, the said contact bus-bars being engageable by the wiper of said one or more selectors; a terminal board secured to the rack and having terminals and jacks horizontally adjacent to each selector position; a plug jack for each selector whereby the selector circuits may become connected or disconnected when the selector is mounted on or demounted from said rack. 110
6. A vertical selector rack; horizontal insulating spacers, one above another; vertical contact bus-bars held in their relative positions by said spacers; a back board carrying a series of jacks and means whereby said bus-bars may engage said jacks. 120
7. A vertical selector rack; vertical contact bus-bars arranged radially around a 130

common centre, each having a free end; horizontal insulating spacers to retain said bus-bars in their relative positions; a back board carrying a series of jacks; and means whereby the free ends of said bus-bars may engage said jacks.

8. A back board carrying two or more series of jacks; a multiple cable whereby each jack in each series is permanently connected 10 to a corresponding jack in each other series; vertical selector racks each having a series of vertical contact bus-bars, each bus-bar having a free end; and means whereby the said selector racks may be removably 15 mounted on said back board, the free ends of said bus-bars engaging the said jacks.

9. A vertical selector rack; vertical contact bus-bars, each having a bent free end, the bends being arranged alternatively in 20 opposite directions, or "staggered;" a series of jacks suitably mounted to receive the bent free ends of said bus-bars; selectors for said rack; and means whereby said selectors may successively engage said bus- 25 bars.

10. A fixed vertical selector rack; vertical contact bus-bars each having a free end; a series of jacks suitably mounted; and means whereby the free ends of said bus-bars engage 30 said jacks; selectors for said rack; and means whereby said selectors may successively engage said bus-bars.

11. Two or more series of jacks; a suitable mounting for same; a multiple cable

whereby each jack in each series is permanently connected to a corresponding jack in each other series; a plurality of selector racks, each having a vertical series of contact bus-bars, engaging said jacks, suitably held in insulating material and arranged 35 radially adjacent to a series of selector positions; pins at each selector position perpendicular to the face of the said rack; a series of jacks horizontally adjacent to each selector position; selectors having frames with 40 holes therein whereby they may be removably mounted on said pins, each selector having a contact member for engaging the said bus-bars; and each selector having a series of plugs to engage the said jacks adjacent to itself.

12. A vertical selector rack; vertical contact bus-bars suitably held in insulating material and arranged in radial relation to a series of selector positions; pins at each selector position perpendicular to face of said rack; a terminal board secured to said rack and having a series of jacks and a series of terminals horizontally adjacent to each selector position; selectors, each having 55 a frame with holes whereby it may be removably mounted on said pins; each selector having a series of plugs to engage the said jacks; and each selector having a rotatable contact member for engaging said bus-bars. 60

In testimony whereof I hereunto affix my signature.

ALTON E. STEVENS.
